**COMBINED DESK AND PROJECTION CHAMBER
FOR AN ELECTRON MICROSCOPE**

Johan Catharinus Hendrikus de Jongh, Eindhoven,
Netherlands, assignor to North American Philips
Co. Inc.

Filed Jan. 25, 1967, Ser. No. 5,620

Term of patent 14 years

Claims priority, Switzerland Aug. 22, 1966

(Cl. D26—5)

FIG.1

FIG.2

FIG. 3

FIG. 4

FIG. 5

FIG. 6

FIG. 1 is a perspective view of a combined desk and projection chamber for an electron microscope showing my new design;

FIG. 2 is a reduced top plan thereof;

FIG. 3 is a front view thereof;

FIG. 4 is a rear view thereof;

FIG. 5 is a right side elevation thereof;

FIG. 6 is a left side elevation.

The broken lines are shown for illustrative purposes only.

I claim:

The ornamental design for a combined desk and projection chamber for an electron microscope, as shown and described.
